Assistant Examiner — Steven Czyz

(74) Attorney, Agent, or Firm — Crowe & Dunleavy, P.C.

(57) **CLAIM**

The ornamental design for a louvered walker, as shown and described.

DESCRIPTION

FIG. 1 is a front perspective view of a louvered walker showing my new design;

FIG. 2 is a front view thereof;

FIG. 3 is a top view thereof;

FIG. 4 is a bottom view thereof;

FIG. 5 is a rear view thereof;

FIG. 6 is a right side view thereof; and,

FIG. 7 is a left side view thereof.
